CLAIM

The ornamental design for a fluorometer display screen with graphical user interface, as shown and described.

DESCRIPTION

FIG. 1 is a view of a first embodiment of a fluorometer display screen with graphical user interface showing our new design; and,

FIG. 2 is a view of a second embodiment thereof. The broken line showing of the fluorometer is included for the purpose of illustrating environmental structure and forms no part of the claimed design. The remaining broken lines illustrate the display screen and portions of the graphical user interface and form no part of the claimed design.
